[57] CLAIM

The ornamental design for a car top carrier, substantially as shown.

DESCRIPTION

FIG. 1 is a rear elevational view of a car top carrier showing my new design;

FIG. 2 is a side elevational view thereof;

FIG. 3 is a bottom plan view thereof;

FIG. 4 is a top plan view thereof;

FIG. 5 is a side elevational view thereof opposite to that shown in FIG. 2; and

FIG. 6 is a front elevational view thereof.
